UNITED STATES PATENT OFFICE

2,609,432

FLASHOVER INDICATOR

Kenneth R. Steen, Portland, Oreg., assignor to
the United States of America as represented by
the Secretary of the Interior

Application July 10, 1950, Serial No. 172,995

2 Claims. (Cl. 177—311)

(Granted under the act of March 3, 1883, as
amended April 30, 1928; 370 O. G. 757)

1

The invention described herein may be manufactured and used by or for the Government of the United States for governmental purposes without the payment to me of any royalty thereon in accordance with the provisions of the act of March 3, 1883, (22 Stat. 625), as amended by the act of April 30, 1928, (45 Stat. 467, 35 U. S. C., 1946 Ed. Sec. 45).

This invention is concerned with the protection of electric power transmission lines. In particular, it is concerned with means for indicating when a tower or pole supporting transmission line conductors has been subjected to flashover. It is related to a co-pending application for patent, Serial Number 172,994 filed by Harold L. Rorden, William E. Scarborough, and Merwin B. Elton.

There are other flashover indicators in the prior art, some of which resemble the present flashover indicator in some aspects of operation. My invention is concerned with improvements over other similar devices, partly in mechanical structure and partly in method of operation.

This flashover indicator is of the type in which operation is accomplished with the release of a signaling device by the ignition of a small charge of explosive powder. The ignition occurs when a high-voltage flashover occurs on the line structure to which the indicator is attached.

A principal object of my present invention is the production of a flashover indicator that is simple and inexpensive, and which will operate reliably under severe service conditions.

Another object is to produce a flashover indicator that will operate reliably when infested with vermin such as cocoon-producing larva. Still another object is to provide electrical connections for the flashover indicator which will provide reliable operation on either steel or wood towers of transmission lines.

What constitutes my present invention is set forth in the following specification with reference to the drawing and succinctly defined in the appended claims.

In the drawing,

Figure 1 is an elevation showing a front view of a preferred embodiment of my invention mounted with appropriate electrical connections on a wood transmission line pole.

Figure 2 is a partly sectional elevation of the same indicator as shown in Figure 1.

Figure 3 is a vertical sectional view of the same indicator as shown in Figure 2, showing the indicator in position prior to operation; taken along the line 3—3 indicated in Figure 2.

Figure 4 is a horizontal sectional view at the

1 elevation indicated by the arrows 4—4 Figure 3.

Figure 5 is an enlarged illustration of the explosive cartridge shown in operative location in Figures 3 and 4.

5 In reference to Figure 1, a flash indicator case 1, made of Bakelite or similar material is supported on a wood pole 2 which supports transmission conductors in the usual way. The flash indicator case 1 is supported on pole 2 by an adjustable conducting strap 3 secured by a bolt 4 which holds also a bracket 5, a flashover rod 6 and an adjusting device 7. Elements 5, 6 and 7 are adapted from the system of lightning grounding on which an application for patent, No. 583,483, has been filed by Harold L. Rorden.

10 On pole 2, below the indicator 1, there is a loop of wire 8 which is connected by a wire 9 to a terminal 11 on the side of the indicator. A connection 12, shown in Figure 3 on the back of case 1, connects strap 3 to the interior of the indicator.

15 Hinged at one side of case 1, near the bottom, there is an indicating closure 14, referred to as an indicating drop, of the shape of one-fourth of a circle. On the face 15 of drop 14, a reflecting surface is provided to make the drop easily seen at night when illuminated by a spot light. The configuration of drop 14 is such that when the indicator is set prior to an indication, the bottom of case 1 is closed by the bottom of indicator 14. The drop is shown open in Figure 1.

20 A wire spring 16 is provided inside the indicator to provide a mechanical force on drop 14 tending to force the drop open.

25 The drop, under normal conditions, is held in the closed position by an explosive link 22 made of a glass tube containing a charge of powder 23 between the ends of two connecting electrodes 24 and 25. The link 22 is placed in position as shown in Figure 3 in which end 25 of the link rests in a hollow conducting rivet 26 in the back of case 1. Rivet 26 is metallically connected to a strip 12 arranged to be in contact with strap 3 when mounted on pole 2.

30 The front end 24 of cartridge 22 is supported in a hollow conducting rivet 27 connected to terminal 11. A hole 28 in the face 15 of drop 14, coaxial with the centers of rivets 26 and 27 engages the body of cartridge 22 when cartridge 22 is in place as shown in Figure 3. Cartridge 22 is placed in position by lifting closure 14 into the closed position shown in Figures 2, 3, and 4 and inserting cartridge 22 through hollow rivet 22 and 35 through hole 28 so the end 25 rests in rivet 26.

Figure 4 is a horizontal sectional view at the

Cartridge 22 then, in bending moment, resists the force of spring 16 holding closure 14 in position against the opening force.

When a flashover occurs on pole 2, a potential difference is set up between strap 3 and wire 8 sufficient to flash over in cartridge 22 between electrodes 24 and 25 exploding powder charge 23. The tube of cartridge 22 is shattered by the explosion of powder 23 so the support formerly provided to hold drop 14 up in the closed position no longer exists. Drop 14 then is opened by the force of spring 16 into the position shown in Fig. 1.

In reference to the co-pending application for patent referred to above, the electrical principles of operation therein are identical with those in my invention. Cartridge 22 is substantially the same for both devices. The difference between these two inventions is that whereas in the earlier one cartridge 22 was held by metallic clips which placed cartridge 22 in cantilever stress, my invention supports the load of closure 14 in the middle of cartridge 22 between the two ends 24 and 25 which are both supported against the bending load. This tends to prevent mechanical creepage of electrodes 24 and 25 in cartridge 22 and to prevent accidental breakage. It is easier in my invention to insert cartridge 22 when setting the device. All that is required in my invention is to lift closure 14 to the closed position and insert cartridge 22 with a single movement through rivet 27 and hole 28, and into rivet 26. The delicacy of adjusting a metal clip and a metal catch as required in the earlier device is avoided.

The mechanical arrangement shown in the drawings is one found by experience to be practical and economical. This arrangement, however, is subject to considerable variation. It is obvious, for example, that the hole 28 in drop 14 could be eliminated and that the same result could be accomplished by a projection at the edge of the face 15 arranged to engage cartridge 22.

Any similar arrangement that enables cartridge 22 to support closure 14 in the simple way generally indicated would be sufficient.

The essential features distinguishing my invention from the prior art are claimed as follows:

1. In a flashover indicator the combination of an insulating case, an indicating drop hinged to be held in said case normally and to drop therefrom when released, coaxial openings in said case and in said drop and an explosive shatterable cartridge in said coaxial openings in said case and drop, said cartridge being placed in said openings in double shear to hold said drop normally in closed position.

2. In a flashover indicator the combination of an insulating case, a hinged indicating drop normally held in said case against the force of a spring in said case, coaxial openings in said case and in said drop, conducting annular fittings in the openings in said case, and an explosive shatterable cartridge supported in said openings and arranged to resist by shearing strength the opening pressure of said spring, the arrangement being that with sufficient potential difference between said annular fittings said potential difference explodes and shatters said cartridge releasing said drop to open position.

KENNETH R. STEEN.
